UNITED STATES PATENT OFFICE

2,015,456

WINDOW LATCH

Adrien R. Mellor, Beaumont, Calif.

Application August 10, 1933, Serial No. 684,574

1 Claim. (Cl. 292—169)

The invention relates to a latch for frames of screen windows and storm windows, and has for its principal object the provision of a latch that will automatically catch and hold a latch bolt on the bottom rail of an outside screen window frame or frame of a storm window, and that is so constructed that the latch cannot be operated when the lower sash of the window casing is in its lowered position, and the operating means is also contained within an open ended casing, so that operation of the latch to release the window frame cannot be accomplished from the outside of the house whether the lower sash is closed or open.

15 A further object of the invention is the provision of a latch of the type referred to that is reasonable in cost of manufacture, that is simple in operation, and that is effective in providing a latch for the purpose stated.

20 The invention will be described in detail hereinafter and will be found illustrated in the accompanying drawing, in which

Figure 1 is a fragmentary view of a window casing and lower sash and the bottom rail or a screen or storm window frame, showing the latch in position relatively thereto, the parts being shown unlatched.

25 Figure 2 is a view similar to Figure 1 with the latch member shown in section, and the parts being shown in latched position.

30 Figure 3 is a front view of the latching mechanism.

Figure 4 is a rear view.

35 Figure 5 is a vertical sectional view on a plane indicated by the line 5—5 of Figure 1.

Figure 6 is a horizontal sectional view on a plane indicated by the line 6—6 of Figure 3, and

40 Figure 7 is a detail view in elevation of a modified construction of latch bolt.

In the drawing similar reference characters are used to designate corresponding parts in all of the views.

45 In the drawing is shown a window casing A in which is mounted the usual sliding window sash B, and shown in connection therewith the frame of a storm window or screen window C, the sill D of the casing being inclined outwardly and downwardly from the lower sash B, the usual practice to shed rain water.

50 Secured to the bottom rail of the frame C is a latch bolt 10 that is provided with a threaded stem 11, the sides of the latch bolt 10 being flattened as shown at 12 to receive the jaws of a wrench for fastening it in the frame. The extremity of the latch bolt 10 is tapered as shown at 13, and said tapered portion on the under side ends with a recess or depression 14 to be engaged by a latching member to be hereinafter described. In Figure 7 the latch bolt indicated at 10' and having a threaded stem 11' is pro-

vided with a polygonal shoulder 12' in lieu of the flattened side 12 hereinbefore described, to receive the jaws of a wrench in turning the bolt.

5 The means for engaging the latch bolt 10 is enclosed within a housing 15 having a substantially U-shaped wall 16, the side portions of said U-shaped wall being divergent as shown at 17. The lower edges of the side walls 17 are turned outwardly as shown at 18 and returned under 10 the portions 19 as shown at 19 to clamp a base plate 20 therebetween. The base plate 20 and parts 18 and 19 are provided with registered openings 21 to receive screws or other driven fastenings 22 to secure the casing in position on the 15 window sill D, as shown, and the lower wall of the casing is inclined slightly as shown in Figures 1 and 2 to conform to the inclination of sill D, so that the remainder of the casing will be in vertical position when secured, and the inner end 20 of the casing which is open, as shown at 23, will snugly engage the lower rail of the lower sash B to prevent operation of the latching members inside of the casing, that will be hereinafter described, when the lower sash is in a closed position.

25 The base plate 20 has an upturned portion 24 that provides a wall closing the outer end of the casing 15 and said wall 24 has an opening 25 therein to receive the latch bolt 10 when the frame member C is in a closed position as shown in Figure 2. In order to hold the latch bolt in a latched position, there is provided a latching plate 26 having an opening 27 therein that registers at times with the opening 25, the lower wall 30 of the opening 27, designated 28, by engaging in the recess 14 locks the bolt in engagement in the casing and the window frame C in closed position. Plate 26 is slidably mounted between grooved 35 guides 29 secured to the wall 24, and the plate 26 is provided with a flange 30 that is engaged by a helical spring 31 of expandable type and that serves to normally hold the plate in engaging position as shown in Figure 2. The helical spring 40 as shown has been selected for illustration, but it will be apparent that any other type of expandable spring may be substituted therefor without changing the spirit of the invention.

32 is a partition in the casing 15 that is connected to the wall 24 by means of brace members 33, and the partition 32 has an offset forming a shoulder 34 intermediate of its upper and lower ends, said shoulder 34 providing a stop to limit the movement of the plate 26 under the impulse 45 of the spring 31. Journalled in the wall 24 and partition 32 is a shaft 35 on which is secured a cam 36, that when the shaft 35 is rotated, engages the plate 26 to move the plate toward the position for registration of the opening 27 therein 55 with the opening 25 in the wall 24, and to release 60

the latch bolt 10 when in a latched position. 37 is a knurled head on the shaft 35 for manual turning of the shaft as stated.

It is to be understood that the invention is not restricted to the precise or exact arrangement of parts illustrated and described, as details of construction may be modified and rearranged without departing from the spirit of the invention, the scope being limited only by the terms 10 of the appended claim.

What is claimed is:—

A latch member, comprising a housing having an end wall provided with an opening for the entrance of a keeper stud, a latch plate slidably

mounted on said end wall and over said opening, and having an opening therein to align with the opening in the wall, an angularly related flange on said plate, an expansible spring engaging said flange to normally hold the plate in latching position, a partition in said housing having an offset providing a shoulder to engage said flange and limit the movement of said plate to latching position, a shaft rotatably mounted in said partition and end wall, and a cam on said shaft to 10 engage the latch plate and move it against the tension of said spring with the opening therein aligned with the opening in the end wall.

ADRIEN R. MELLOR.
